H. L. CARSON AND R. A. HUNTER,
DETACHABLE MANGLE,
APPLICATION FILED SEPT. 13, 1920.

1,398,501.

Patented Nov. 29, 1921.

UNITED STATES PATENT OFFICE.

HARRY L. CARSON AND ROBERT A. HUNTER, OF FORT WORTH, TEXAS.

DETACHABLE MANGLE.

1,398,501.

Specification of Letters Patent. Patented Nov. 29, 1921.

Application filed September 13, 1920. Serial No. 409,764.

To all whom it may concern:

Be it known that we, HARRY L. CARSON and ROBERT A. HUNTER, both citizens of the United States of America, residing at Fort 5 Worth, in the county of Tarrant and State of Texas, have invented certain new and useful Improvements in Detachable Mangles, of which the following is a specification.

Our invention relates to mangles for use 10 with washing machines and more particularly to detachable mangles which can be used with various types of driving heads; and the object is to provide mangles which are simple in construction and operation and 15 which will be highly efficient in ironing the goods and to provide a simple means of heating the mangle and maintaining a steady or substantially uniform temperature during 20 operation and which can be easily attached to a driving head and easily detached therefrom. Other objects and advantages will be 25 fully explained in the following description and the invention will be more particularly pointed out in the claim.

Reference is had to the accompanying drawings which form a part of this application.

Figure 1 is a front elevation of the improved mangle, showing the same attached 30 to a wringer driving head. Fig. 2 is an end elevation, partly in section and parts broken and other parts omitted. Fig. 3 is a broken vertical section, Figs. 2 and 3 being enlarged to show more clearly the construction of the 35 several parts.

Similar characters of reference are used to indicate the same parts throughout the several views.

Our invention is illustrated with one of the 40 types of driving heads of wringer attachments. The wringer or driving head 1 is provided with the usual power connecting shaft coupling 2. The mangle is provided with a frame having upright members 3, U-shaped cap member 5 attached to uprights 3 and 4, and side slabs or bars 6 attached to the members 3 and 4. The members 3 and 4 are provided with inwardly projecting flanges to which the members 5 and 6 are 45 attached.

The means for ironing the goods consists of a revolving drum 7 which is loosely mounted on a pipe 8 and is driven by friction as hereinafter explained. The drum 7 has a 55 smooth periphery and has apertures 9 in the

ends for admission of air. Means are provided for heating the drum 7. The pipe 8 is fixed against rotation by a collar 10 which is rigid with the pipe 8 and is prevented from turning by dowel pins 11 which are 60 rigid in the upright 3. The pipe 8 has perforations 12 for escape of gas to be burned in the drum 7. The pipe 8 is provided with an air mixer 13 which is adjustable on the pipe 8 and may be held at different adjustments by a set screw 14. The gas is admitted through a nipple 15 and the amount of gas admitted may be regulated by a needle valve 16. The gas is lighted at the point 17 and the force of the air causes the heat 70 and flame to be directed toward the opposite end of the drum or toward the driving head 1.

The mangle is provided with a power shaft 18 which is journaled in stationary bearings 19 which are mounted in the uprights 3 and 4 and supported and held in place by the rods 20 with their nuts 21. The side bars 6 are attached to uprights 3 and 4 by the bolts 20 and bolts 22 with nuts 23.

The pipe 8 is mounted in movable bearings 24. These bearings are vertically movable in the uprights 3 and 4 and rest on springs 25 which are seated on bearings 24. The bearings 24 may be set at different positions 85 by the set screws or bolts 26 which may be screwed down more or less to compress the springs 25 and 25'. A cap 24' which has a socket for the screw 26 and a seat for the spring 25' forms the connection between the spring 25' and the screw 26. It will be understood that both ends of the mangle are provided with similar or duplicate equipment of parts. With this arrangement of operating elements, the drum 7 may be 95 pressed more or less on the goods to be passed between the drum 7 and the co-operating drum 27 which is carried by the power shaft 18. The ironing drum 7 is thus held suspended between the springs 25 and 25' and in the bearings 24 which are vertically movable in the uprights 3 and 4. The ironing drum is thus held yieldingly on the goods which are passing through the mangle.

The pressing drum 27 is prepared by placing a felt covering 28 next to the shaft 18 and then winding a sheet of cloth on the felt 28 and the cloth is wound or wrapped on the drum in convolute form until the required thickness is attained to form a suit- 110

able pad which is more or less yielding. The shaft 18 is driven by the gearing of the driving head 1.

The mangle is bolted or riveted to the head 1 by bolts or rivets passing through the upright 4 and through the adjacent frame piece of the driving head. An inclined table or receiving plate 29 is attached to the mangle frame to receive the goods which are going to the pressing members of the mangle and inclined discharge plate 30 is attached to the mangle frame from which the goods may be taken. Various changes in the sizes, proportions, construction and arrangement of the several parts may be made without departing from our invention.

What we claim, is,—

The combination of a driving head and a mangle detachably connected to said head,

said mangle having a revolving drum pad driven by said head, a hollow pipe extending through said mangle, vertically movable bearings for said hollow pipe, means for adjusting and applying pressure to said bearings to hold said pipe at different adjustments relative to said drum, a hollow ironing drum mounted loosely on said pipe and adapted to be driven by friction of goods passing between said drum pad and said ironing drum, said pipe having perforations for directing gas jets within said drum, and means for supplying gas and air through said hollow pipe for heating said drum.

In testimony whereof, we set our hands, this 2nd day of September, 1920.

HARRY L. CARSON.
ROBERT A. HUNTER.
